(57) **CLAIM**

The ornamental design for a protective glove, as shown and
described.

DESCRIPTION

FIG. 1 is a perspective view of a first embodiment of a
protective glove according to the present design;

FIG. 2 is a front view thereof;

FIG. 3 is a rear view thereof;

FIG. 4 is a side view thereof;

FIG. 5 is a side view thereof;

FIG. 6 is a top view thereof; and

FIG. 7 is a bottom view thereof.

FIG. 8 is a perspective view of a second embodiment of the
protective glove of FIGS. 1 through 7;

FIG. 9 is a front view thereof;

FIG. 10 is a rear view thereof;

FIG. 11 is a side view thereof;

FIG. 12 is a side view thereof;

FIG. 13 is a top view thereof; and,

FIG. 14 is a bottom view thereof.

The broken lines represent portions of the protective glove
and form no part of the claimed design.

Although shown in the context of a left hand glove, an
embodiment of the present invention also may be incorpo-
rated in a right hand glove, wherein the right hand glove is
a mirror image of the left hand glove depicted in the FIGS.
